RELAY SYSTEM FOR DIESEL ELECTRIC
LOCOMOTIVES

Clarence S. Snavely, Churchill Borough, Pa., assignor to The Union Switch & Signal Company, Swissvale, Pa., a corporation of Pennsylvania

Application March 6, 1947, Serial No. 732,771

3 Claims. (Cl. 290—17)

1

My invention relates to relay systems and particularly to relay systems adapted to provide an accurate response to sensitive relays of the meter type. It has been found desirable in some relay applications to initiate or change a control only upon the closure of relay contacts but not upon the opening of contacts. This arrangement is advantageous in applications where sensitive relays of the meter type are used, and is occasioned by the fact that the contact structures of relays of this type are inherently fragile and limited to extremely light duties so that the contacts may be used to establish a circuit through which current is initiated but are unable to withstand the arcing and burning which accompanies the interruption of a current at such contact elements.

It has also been found necessary in these applications to provide a system arranged so as to check the integrity of the circuit elements used to establish and maintain the operated condition of the apparatus. In other words, the system organization is such that the apparatus assumes or maintains its operated position only so long as energy is supplied thereto, so that any failure of the circuit elements supplying energy to the apparatus for establishing and maintaining its operated condition will either prevent operation of the apparatus to its operated position, or will result in failing to maintain the apparatus in its operated position.

It is an object of my invention to provide a novel and improved relay system incorporating a repeater relay cooperating with a master relay and arranged so as to obtain operation of the repeater relay only when contacts of the master relay close but not when such contacts open.

Another object is to provide a novel and improved relay system wherein a master relay controls a repeater relay between normal and operated conditions by circuits arranged to effect operation of the repeater relay only when the master relay contacts close and in which circuits the master relay contacts are never required to interrupt a flow of current.

A further object is to provide a system of the type described above, in which the relays and circuits are arranged so that the repeater relay assumes and maintains its operated condition only so long as it is energized.

The above mentioned and other important objects and characteristic features of my invention are obtained by providing a master relay with a two-winding repeater relay. The master relay establishes through one of its contacts a pick-up

2

circuit for the repeater relay including the two windings of the relay cumulatively energized, the repeater relay when energized establishes a stick circuit including one of its windings and shunting the other of its windings and the contact of the master relay in the pick-up circuit, and the master relay also establishes through another of its contacts a release circuit including the other winding of the repeater relay energized in opposition to the stick winding, with the stick contact of the repeater relay interrupting the release circuit carried through the contact of the master relay.

I shall describe one form of apparatus embodying my invention and shall then point out the novel features thereof in claims.

In the accompanying drawings, Fig. 1 is a diagrammatic view illustrating a preferred form of apparatus embodying my invention. Fig. 2 is a diagrammatic representation of the different conditions of operation of repeater relay KP obtaining according as (a) current is rising in master relay MR, or (b) current is falling in master relay MR.

Referring to Fig. 1, the reference character MR designates a sensitive relay of the meter type schematically shown as comprising a horse-shoe shaped permanent magnet 1 provided with confronting pole pieces 2 between which a magnetizable member 3 is pivotally mounted for rotation about an axis perpendicular to the plane of magnet 1. The member 3 carries a pointer or finger 4 and is biased in the customary manner, as by a spring, to cause finger 4 to assume a first position which may, for example, be an extreme left-hand position as viewed in Fig. 1. Member 3 also is provided with a coil or winding 5 which when energized by current of suitable polarity creates a flux which cooperates with the permanent magnetic flux existing between pole pieces 2 to rotate member 3 in a clockwise direction (as viewed in Fig. 1) to a position determined by the strength of the biasing spring and the relative values of the permanent magnetic field and flux due to current in winding 5. Relay MR also includes a first contact element 6 disposed to engage finger 4 when that finger is positioned in its first or left-hand position, and a second contact element 7 disposed to engage finger 4 when member 3 is rotated clockwise to the position where finger 4 occupies another extreme or right-hand position as viewed in Fig. 1. The arrangement is thus such that finger 4 engages contact element 6 when the energy of coil 5 is below the level,

hereinafter referred to as the lower level, at which member 3 operates finger 4 out of engagement with element 6, and finger 4 engages contact element 7 when the energization of coil 5 is at or above the level, hereinafter referred to as the upper level, at which member 3 is rotated to position finger 4 in engagement with element 7. When coil 5 is energized at a value intermediate the lower and upper levels just mentioned, finger 4 is then disposed intermediate contact elements 6 and 7 and is disengaged from each of those elements. It is to be understood of course that the various elements of relay MR are suitably housed and that external terminals may be provided on the housing for establishing circuit connections with the relay elements.

The contact elements 6 and 7 and finger 4 of relay MR are proportioned in accordance with the torque available for operation of member 3 and assuming that relay MR is designed to operate on a very low degree of energization of coil 5 it will be assumed that finger 4 and contact elements 6 and 7 are of the light duty type capable of handling relatively low currents ranging in the milliamperes using a low voltage source capable of delivering only a few volts.

In order to detect the operation of relay MR, I provide a repeater relay of the biased polar type such as that shown and claimed in Letters Patent of the United States No. 2,283,270, granted on May 19, 1942, to Robert M. Laurenson for Electrical Relay. Relay KP comprises two windings 8 and 9 and an armature suitably biased as explained in Patent No. 2,283,270, to one extreme position which I shall term a normal position, and operable to another extreme position, which I shall term a reverse position, only when the net resultant flux in the relay due to windings 8 and 9 is in the proper direction and is sufficient in magnitude to overcome the armature bias. The windings 8 and 9 are provided on the relay in such a manner that either winding creates flux of the proper direction to counteract the bias of the armature and operate that armature to its reverse position only when current flows through the winding in the direction indicated in the drawing by an arrow associated with that winding, or from left terminal to right as viewed in Fig. 1. Accordingly, energy flowing in either winding from its right terminal to its left not only is ineffective to create flux of the proper direction to counteract the armature bias, but on the other hand creates a flux tending to assist the bias of the armature. This type of relay responds quickly to relatively low energy levels in the relay and will operate properly on the limited amount of power that can, without causing injury to the elements, be passed through the contacts of master relay MR.

Relay KP is controlled by relay MR through the medium of circuits supplying current to relay KP from a suitable source, such as a battery having its opposite terminals designated by the reference characters B and C with the current from the source being assumed to flow from terminal B through various circuit elements to terminal C. A pick-up circuit for relay KP may be traced from terminal B through contact 6-4 of relay MR and windings 8 and 9 of relay KP, in series, to terminal C. It will be noted that the direction of current flow in the pick-up circuit is such that both windings 8 and 9 are traversed by energy from left terminal to right so that the two windings act cumulatively to generate a flux opposing and counteracting the bias of the arma-

ture of relay KP to cause that armature to operate to its reverse position. It will also be noted that with windings 8 and 9 connected in series in the pick-up circuit the resistances of the windings are additive to limit the current flow in the circuit but due to the cumulative action of the fluxes the magnetomotive forces produced at the limited current value is sufficient to cause relay KP to operate its armature to its reverse position. This operation of relay KP drives contact finger 10 carried by the armature of relay KP, into engagement with contact element 12 and establishes a stick circuit which may be traced from terminal B through contact 12-10 of relay KP, and winding 9 from its left terminal to its right terminal and then to terminal C. The stick circuit places a short circuit across contact 6-4 of relay MR and winding 8 of relay KP, so that the resistance of that winding accordingly is cut out of circuit with winding 9 with the result that the value of current caused to flow in winding 9 under these conditions is greater than the current flow which obtains when windings 8 and 9 are in series and contact 10-12 of relay KP is open. The resistances and number of turns of windings 8 and 9 are preferably so proportioned that with winding 8 shunted, winding 9 is energized at a level such as to produce substantially the same value of magnetomotive force that is produced when windings 8 and 9 are energized cumulatively in series. The stick circuit of relay KP accordingly is effective when completed to hold its armature in its reverse position and will do so in the event that contact 6-4 of relay MR is opened. If this contact is opened it is to be noted that the contact merely interrupts a shunted circuit path so that there is no danger to the sensitive light duty contact elements due to arcing or burning which accompanies the interruption of a current through contact elements.

Assuming that relay KP is held energized over its stick circuit and that contact 6-4 of relay MR has opened without danger to its parts, relay KP will remain energized until such time as relay MR closes its other contact 4-7. This contact establishes a release circuit which extends from terminal B through contact 12-10 of relay KP, winding 8 of relay KP from its right terminal to left, and contact 4-7 of relay MR to terminal C. It will be noted that the flow of current in winding 8 due to the release circuit is in the direction to create flux aiding the armature bias, and that winding 8 accordingly creates a flux opposite in direction to the flux created by winding 9 energized in its stick circuit. The windings 8 and 9 are now connected in parallel circuit paths across the source and because of the previously mentioned proportioning of the parts each winding will be capable of creating a flux substantially cancelling the flux created by the other winding, so that the net resultant flux created by the two windings would have a value of substantially zero magnitude in relay KP if the energized conditions of the two windings were maintained. Before such a total cancellation of flux obtains, however, the resultant flux in relay KP will decrease to a point below that required to maintain the armature in its reverse position in opposition to its bias, with the result that the armature will respond to its bias and operate to its normal position to open contact 12-10 and thereby deenergize both windings 8 and 9. The flux in relay KP due to windings 8 and 9 will therefore decay to a zero value.

With relay KP in its normal position, contact

4—7 of relay MR may open or close without effecting any change in the operation of repeater relay KP and without interrupting any current-carrying circuit path so that no danger will be experienced by the contact elements of relay MR due to arcing or burning which accompanies the interruption of a current through contact elements.

After relay KP has operated to its normal position due to the establishment of its release circuit by the closure of contact 4—7 of relay MR, the relay KP will remain deenergized and in its normal position until the relay MR is caused to close its contact 6—4 and re-establish the previously traced pick-up circuit for relay KP, whereupon the relay armature is operated to its reverse position to re-establish its stick circuit.

From the foregoing description it will be seen that repeater relay KP is caused to operate between its normal and reverse positions in response to the closure of contacts of master relay MR and that the contacts of the repeater relay are utilized in such a manner as always to interrupt the circuits carrying current so that the contacts of the master relay are never required to perform this function.

A typical application of a relay system of the type hereinbefore described is represented in Fig. 1 wherein the relay system is represented controlling a prime mover 15 operatively connected with an electrical generator 16 which has its terminals connected through a precision shunt 17 to a conventionally represented load 18. Terminals 19 located at spaced points on shunt 17 are connected to the opposite ends of coil 5 of master relay MR so as to impress the voltage drop across the shunt between these terminals on the coil. Although this voltage drop may be so small as to be practically negligible with respect to the drop across load 18, the parts of relay MR are designed to reflect the relative values of current flow in the load circuit and the relay system operates to establish different controls depending upon such relative current values. For example, in a specific application where the relay system has been found to be particularly advantageous, the load 18 comprises the driving motors of a Diesel electric locomotive in which the prime mover 15 and generator 16 shown in the drawing correspond respectively to the Diesel power plant and the electrical generating equipment of the locomotive. The generator 16 in such applications may be required to furnish load currents of the order of several thousand amperes. Master relay MR connected across terminals 19 provides a measure of the value of current in the load circuit and may, for example, be arranged to close its contact 6—4 when the load current is at or below a lower level, say 1500 amperes; to close its contact 4—7 when the load current is at or above an upper level, say 2000 amperes; and to open both contacts 6—4 and 4—7 when the load current is intermediate the lower and upper levels.

In such an application the operation of the apparatus is as follows: The apparatus is assumed to be in the position illustrated in the drawing wherein the load current will be above the upper level because contact 4—7 of relay MR is closed. Relay KP is deenergized and its normal contact 11—14 is closed so that this contact may be utilized to establish a first or normal condition of control of prime mover 15 as indicated in the drawing.

Assuming that the current in the load circuit is falling, contact 4—7 of relay MR will open when the load current drops below the upper level and finger 4 will be positioned intermediate contact elements 6 and 7. The opening of contact 4—7 will have no effect on the operation of relay KP and obviously will not interrupt any flow of current. The contact 4—7 may therefore close or open at will according as the load current drops below or rises above the upper level but this operation of the contact of relay MR will not be reflected by any change in the control condition established over prime mover 15.

Relay KP will remain deenergized until such time as the load current drops to or below the lower level and this condition is reflected by relay MR closing its left-hand contact 6—4. When this happens the previously mentioned pick-up circuit of relay KP is established to energize windings 8 and 9 cumulatively in series to cause the armature of relay KP to operate to its reverse position. This operation results in contact 10—12 of relay KP closing to establish the previously mentioned stick circuit of relay KP and to place a dead short-circuit around winding 8 and contact 6—4 of relay MR. Reverse contact 11—13 of relay KP also is closed and may be utilized as indicated in Fig. 1 to establish a second or reverse condition of control of prime mover 15.

With winding 9 of relay KP energized over its stick circuit, contact 6—4 of relay MR may open or close at will to reflect the load current dropping below or rising above the lower level at which relay MR operates finger 4 out of engagement with contact element 6; but any such operation of contact 6—4 of relay MR will have no effect upon operation of relay KP and will not be reflected by any change in the condition of control established over prime mover 15. Also, such operation of contact 6—4 will not initiate or interrupt any current flow because the contact is positioned at this time in a circuit path across which the dead short-circuit is connected.

Relay KP will remain energized and in its reverse position until relay MR closes its contact 4—7 to reflect that the load current has risen to or above the upper level. When this happens the previously mentioned release circuit is established for winding 8 of relay KP and that winding creates a flux which opposes the flux due to current in the stick winding 9; whereupon relay KP will release, that is the armature will respond to its bias and operate to its normal position. This results in the opening of contact 12—10 of relay KP to deenergize both windings 8 and 9. Normal contact 11—14 of the relay also will close and will re-establish the first or normal condition of control of prime mover 15. The apparatus accordingly will be restored to the condition in which it is illustrated in the drawing.

It is to be noted that the system provides a check on the integrity of the elements of the pick-up and stick circuits for relay KP in that the relay must be energized to assume and maintain its reverse or operated position, consequently any failure of the elements of the pick-up circuit will prevent the establishment of the current flow required to operate relay KP to its reverse position; while any failure of the elements of the stick circuit will interrupt the current flow required to maintain relay KP in its reverse position. It follows that because of the biasing features of relay KP, it will assume and maintain its reverse position only if the circuit elements of the pick-up and stick circuits remain intact.

thereby assuring that a failure of any circuit element will result either in failure of relay KP to operate, or in restoration of the relay to its normal position.

It is also to be noted that the relay system functions in such a manner that once relay KP is picked up it remains picked up until contact 4-7 of relay MR closes, and once relay KP is released it remains released until contact 6-4 of relay MR closes. The condition of relay KP established upon closure of either contact of master relay MR is therefore maintained until the other contact of the relay subsequently closes, and the released or picked-up condition of relay KP in the intermediate range of energization of relay MR is determined by the particular contact of the master relay that last caused a change in operation of relay KP. As indicated in Fig. 2, the condition assumed by relay KP in the intermediate position of master relay MR (where finger 4 is disengaged from both contact elements 6 and 7) accordingly differs depending upon whether the last operation of relay KP was occasioned by a contact of relay MR closed because of current rising in the load circuit, or falling in such circuit. Diagram 2(a) of the drawing represents the operation of relay KP obtaining when current in the load circuit rises in value from below the lower level to above the upper level, the relative values of current being indicated along the horizontal line. This diagram indicates that in such case relay KP, which was in its picked-up position with current in the load circuit below its lower level, remained picked up until the upper level of load current was reached, whereupon relay KP was caused to release. Diagram 2(b) represents the operation of relay KP when current in the load circuit falls from above the upper level to below the lower level. This diagram indicates that in the case of falling load current relay KP, which was released with current in the load circuit above its upper level, remains released in the intermediate range of load current and until the load current reaches its lower level, whereupon relay KP picks up.

An advantage of a relay system embodying my invention is the arrangement whereby a master relay controls a repeater relay by circuits arranged to effect operation of the repeater relay only when the contacts of the master relay close, and in which circuits the master relay contacts are never required to interrupt a flow of current. The arrangement therefore permits a master relay of the sensitive meter type having inherently fragile contacting elements to establish different controls with the minimum of damage to the contacting elements of the relay.

Although I have herein shown and described but one form of relay system embodying my invention, it is understood that various changes and modifications may be made therein within the scope of the appended claims without departing from the spirit and scope of my invention.

Having thus described my invention, what I claim is:

1. A relay system comprising a two-winding relay having contact means operated between opened and closed positions according as said relay is released or picked up respectively, contact elements movable to first and second circuit closing positions, a source of current, a pickup circuit including said source and both of the relay windings connected in series to create additive fluxes to pick up the relay and completed by said contact elements in their said first circuit closing po-

sition, whereby the picking up of said relay checks the integrity of both windings of said relay and their respective circuit connections, a holding circuit including said source and one of said two windings and completed by said contact means in its closed position, said holding circuit establishing a short circuit across the portion of the said pickup circuit that includes the other of said two windings and said contact elements in their first circuit closing position, and a release circuit including said source and said other winding and said contact means in its closed position and completed by said contact elements in their second circuit closing position, said other winding when energized in its release circuit creating a flux opposing that set up by the said one winding energized in its holding circuit.

2. A relay system for controlling the propulsion system of a Diesel-electric locomotive having a prime mover connected through an electrical generator and a load circuit to the wheel driving motors of said locomotive, said relay system comprising a meter type master relay responding to energy from said load circuit and having contact elements including a first and two cooperating second elements relatively movable to first and second circuit closing positions in which said first contact element respectively engages one or the other of said two second contact elements, a two-winding polar biased repeater relay having an armature biased to a first position and operable to a second position when the net resultant flux in said relay is in a given direction and above a given level, contact means operated by said armature comprising a fixed member and a single cooperating movable member operated to opened or closed positions with respect to the fixed member according as said armature occupies its said first or second position respectively, a source of current, a pickup circuit including said source and both windings of said repeater relay connected in series to create additive fluxes having a net resultant in said given direction and above said given level to operate said armature to its said second position and completed by the contact elements of said master relay in their said first circuit closing position, whereby the operation of said armature of said repeater relay to its said second position checks the integrity of both windings of said repeater relay and their respective circuit connections, a holding circuit including said source and one of said two windings of said repeater relay and completed by the movable member of said contact means in its closed position, said holding circuit shunting the other of said two windings of said repeater relay and the contact elements of said master relay in their said first circuit closing position, and a release circuit including said source and the movable member of said contact means in its closed position and said other winding of said repeater relay and completed by the contact elements of said master relay in their said second circuit closing position, said other winding when energized in its release circuit creating a flux opposing that set up by the said one winding energized in its holding circuit.

3. In combination with a meter type master relay having contact elements including a first and two cooperating second elements relatively movable to first and second circuit closing positions in which said first contact element respectively engages one or the other of said two second contact elements, a two-winding polar biased repeater relay having an armature biased to a first

position and operable to a second position when the net resultant flux in said relay is in a given direction and above a given level, contact means operated by said armature and comprising a fixed member and a single movable member operated to an open or closed position with relation to said fixed element according as said armature occupies its said first or second position respectively, a source of current, a pickup circuit including said source and both windings of said repeater relay connected in series to create additive fluxes having a net resultant in said given direction and above said given level to operate said armature to its said second position and completed by the contact elements of said master relay in their said first circuit closing position, whereby the operation of said armature of said repeater relay to its said second position checks the integrity of both windings of said repeater relay and their respective circuit connections, a holding circuit including said source and one of said two windings of said repeater relay and completed by said single movable member of said contact means in its closed position, said holding circuit shunting the other of said two windings of said repeater relay and the contact elements of said master relay in their said first circuit closing position, and a release circuit including said source and said single movable member of said contact means in its closed position and said other winding of said repeater

relay and completed by the contact elements of said master relay in their said second circuit closing position, said other winding when energized in its release circuit creating a flux opposing that set up by the said one winding energized in its holding circuit.
